UNITED STATES PATENT OFFICE.

WM. ORTON WILLIAMS, OF WASHINGTON, DISTRICT OF COLUMBIA.

BRIDLE-REIN.

Specification of Letters Patent No. 27,492, dated March 13, 1860.

To all whom it may concern:

Be it known that I, WM. ORTON WILLIAMS, of Washington city, in the District of Columbia, have invented a new and Improved Bridle-Rein; and I do hereby declare that the following is a full and exact description thereof, reference being had to the accompanying drawings and to the letters of reference marked thereon.

10 The nature of my invention consists in crossing the bridle reins in such a manner that when the reins are held in one hand and moved to the right or left they may exert no counteracting influence on that side 15 of the horse's mouth, opposite to the direction in which you wish him to move, which is the great disadvantage of the reins now in use. This arrangement of the reins has also the advantage of doing away, in 20 most cases, with the martingale since a young horse however restive can not succeed in throwing the reins over his head.

To enable others skilled in the art to make and use my invention I will proceed 25 to describe its construction and operation.

There are three modifications of the same principle, which I shall explain by their appropriate diagrams 1, 2, 3.

In Figure 1 let A and A' represent the 30 rings of the bit, and G D H I and C D E F be, what are termed two "half round" reins crossed at D and held in place by the ring D K (made of whatever material is preferred).

Fig. 2 shows that the spring A often used on the present rein instead of the buckle may be attached with advantage, while the ring L M works in a direction perpendicular to that of D K in Fig. 1. If 40 desired, D K in Fig. 1 may take if preferred the position of L M in Fig. 2.

Fig. 3 shows a pair of reins B E R D and F E G H of which P E G, P O, W E R and W L C are round, passing through each other at E and L.

A F and A' B represent the buckles.

Now the reins in Fig. 1 being on the horse his neck passing through the bridle at O, if the bridle hand is moved toward the left the rein G D H I acting against 50 the right side of his neck pulls on the left side of his mouth, and vice versa.

Fig. 2 also shows the martingale to be used with these reins should the rider wish one.

D K is a single strap with the ring L M attached, through which the crossed reins pass.

What I claim as my invention and desire to secure by Letters Patent is—

The combination of a ring or its equivalent with the crossed reins of a bridle; and this I claim whether combined with the martingale or not.

WM. ORTON WILLIAMS.
